HAIR CURLER

Benjamin Rubin, Chicago, Ill.

Application March 11, 1944, Serial No. 526,019

5 Claims. (Cl. 132—41)

This invention relates to improvements in hair curlers of the kind adapted to be secured to the hair for a length of time sufficient to "set" the curl, and more particularly to hair curlers of well known commercial type having a hollow tubular body, a spring-pressed jaw hinged at one end thereof, to grip the free end of the tress, and a wire loop, also hinged to the body, and adapted to secure said curl along opposite sides of the body.

One of the principal difficulties commercially encountered with hair curlers of the type above described, is their tendency to become unfastened while in use, due mainly to insufficient means for insuring the locking of the wire loop relative to the tubular body.

In such devices the wire loop is usually secured by tension in a notch at the upper end of the hollow body, but after the devices have been repeatedly used, said loops tend to become distorted, and the notches worn, so that the loops readily become unfastened.

The object of the present invention is to provide an improved curler of the general type above described, wherein the loop is provided with a positive locking device which may be securely locked to the end of the tubular body after the curl is formed, and also serves to lock the spring-pressed jaw against said body, while the curler is in use.

The invention may best be understood by reference to the accompanying drawing, in which—

Figure 1 is a perspective view of a curler made in accordance with my invention, with a curl formed thereon, but before the wire loop is finally fastened to the end of the tubular body;

Figure 2 is a detail longitudinal section showing the upper end of the curler (with the curl removed), indicating how the locking cap is swung into position for locking;

Figure 3 is a detail section similar to Figure 2, but showing the cap in locking position; and

Figure 4 is a detail section taken at right angles to Figures 2 and 3.

Referring now to details of the embodiment of my invention illustrated in the drawing, 10 indicates the hollow tubular body of the curler, usually made of perforated metal, and 11 is a spring-pressed jaw hinged as usual near the lower end of the tubular body, so that its elongated laterally curved jaw portion 12 fits along said body to secure the end of the tress preparatory to curling the latter. A loop 13, herein formed of flat wire, has its legs 14, 14 hinged as usual near the lower end of the tubular body, concen-

tric with the hinge of the jaw 11. The free upper end of said loop is of sufficient length to swing over the top of the tubular body 10.

Referring now more particularly to the improved locking means of my invention, I provide a cap or thimble 15, of slightly larger diameter than that of the top end of the tubular body 10 and slidably mounted on the upper end portion 16 of the loop 13, as is best seen in Figure 4. In the form shown, said cap has a pair of depending lugs 17, 17 at opposite sides thereof, which have ears 18, 18 bent inwardly about the proximate sides of the loop 13, as shown, to permit limited endwise sliding movement of said cap relative to said loop. The arrangement is such that the cap can be raised to swing over the top of the body, but when in registering position therewith, as shown in full lines in Figure 2, said cap can then be slid downwardly to fit in locking position over the upper end of said body and the end of the jaw 11, as shown in Figures 3 and 4. Said cap is securely held in its locking position by a lug 19 preferably formed by bending the extreme end of the jaw 11 outwardly. Said lug is adapted to be engaged by tension with a suitable detent on said cap, herein consisting of an aperture 20, formed in the side of the cap. In the form shown, the cap has a downwardly and outwardly flared portion 201

adjacent the aperture 20, forming in effect a cam surface for depressing said lug as the cap is being moved downwardly into locking position. The lug 19 may be unlocked from the aperture 20 when desired, by depressing the jaw with

35 the fingers.

The upper end portion 16 of the loop 13 which fits within the cap 15 is formed with a humped portion 21 at its center, which is adapted to engage in an aperture 22 formed in the center of the cap, when the latter is in fully locked position, as shown in Figure 4. This humped portion serves to hold the cap in centered upright position relative to the hollow body and jaw, thus preventing accidental unlocking of the lug 19 by tilting movement of said cap.

The use and operation of the curler above described will now be understood by those familiar with devices of this character. Usually, the end of the tress to be curled is clamped between the body 10 and the jaw 11, and the tress is then curled by rotating the curler so as to roll the curl about the body and jaw substantially as indicated in Figure 1. The loop 13 is then swung over the upper end of the curler, and the cap 15 is slid downwardly over the end of the hollow

body and jaw, until the lug 19 snaps into locking position in the aperture 20. As thus secured, the curler will remain on the curl until it is positively unlocked by depressing the lug 19, as previously described.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a hair curler, a body member, a jaw member hinged near one end of said body member, a loop member also hinged near one end of said body member, and an annular locking member 15 slidably mounted on the swinging end of said loop member in position to be moved into surrounding relation with the adjacent outer ends of said body member and said jaw member respectively, to hold all of said parts in mutually interlocking relation, and means detachably connecting said jaw member and said locking member to prevent endwise disengagement of the latter.

2. In a hair curler, a body member, a jaw member hinged near one end of said body member, a loop member also hinged near one end of said body member, and a cap member slidably mounted over the swinging end of said loop member in position to fit over and enclose the adjacent outer end of said loop member, said body member and said jaw member respectively, and hold all of said parts in mutually interlocking relation.

3. In a hair curler, a body member, a jaw member hinged near one end of said body member, a loop member also hinged near one end of said body member, and a cap member slidably mounted on the swinging end of said loop member and

adapted to enclose the adjacent outer ends of said body member and said jaw member respectively, to hold all of said parts in mutually interlocking relation, and means affording mutually interlocking engagement between the end of said jaw member and said cap member, to prevent endwise disengagement of the latter.

4. In a hair curler, a body member, a jaw member hinged near one end of said body member, a loop member also hinged near one end of said body member, and a cap member slidably mounted on the swinging end of said loop member and adapted to enclose the adjacent outer ends of said body member and said jaw member respectively, to hold all of said parts in mutually interlocking relation, and means affording mutually interlocking engagement between the end of said jaw member and said cap member, comprising a laterally projecting lug on said jaw member adapted to engage a detent on said cap.

5. In a hair curler, a body member, a jaw member hinged near one end of said body member, a loop member also hinged near one end of said body member, and a cap member slidably mounted on the swinging end of said loop member and adapted to enclose the adjacent outer ends of said body member and said jaw member respectively, to hold all of said parts in mutually interlocking relation, means affording mutually interlocking engagement between the end of said jaw member and said cap member, comprising a laterally projecting lug on said jaw member adapted to engage a detent on said cap, and means on said loop movable into interlocking engagement with said cap when the latter is in locking position on said body, to hold said cap against tilting movement relative to the latter.

BENJAMIN RUBIN.
